UNITED STATES PATENT OFFICE.

AUGUSTINE R. AYERS, OF CHICAGO, ILLINOIS, ASSIGNOR OF ONE-HALF TO JOHN J. BERNET, OF CHICAGO, ILLINOIS.

STOKER FOR LOCOMOTIVES.

1,156,264.

Specification of Letters Patent. Patented Oct. 12, 1915.

Application filed May 26, 1913. Serial No. 769,840.

To all whom it may concern:

Be it known that I, AUGUSTINE R. AYERS, a citizen of the United States, residing at Chicago, in the county of Cook and State of Illinois, have invented certain new and useful Improvements in Stokers for Locomotives, of which the following is a specification.

My invention relates to feeding-means for boiler furnaces, and has particular reference to a novel automatic stoker for locomotives.

I am aware that stokers for locomotives are not broadly new, but there are many objections to the forms heretofore proposed, which objections I eliminate by the present construction. The principal difficulty encountered in the old-style stokers is that if the coal on the chain-grate is completely burned out, which is necessary in order to avoid throwing good fuel into the ash-pan, the fire necessarily becomes so thin at the extreme travel of the chain-grate, that under the intense draft of a steam locomotive a quantity of air would be admitted through the thin portion of the fire, which would be highly detrimental to the steaming qualities of the boiler. That is, holes would be formed through the layer of fire, or the bed of fuel would be completely exhausted and offer practically no resistance to the draft.

I propose to eliminate this objection by the provision of an auxiliary grate adjoining the end of the chain-grate, this auxiliary grate being separate from the chain-grate and having no travel, provision being made, however, for the shaking of the grate and dumping of the accumulated ash. By this construction I am enabled to carry a full thickness of fire over the grate, the complete combustion of the fuel taking place on the auxiliary grate. The unburned fuel will be forced off the chain-grate on to the auxiliary grate and may heap or pile up to a certain extent on the auxiliary grate, thus providing adequate thickness of fuel to prevent the thinning of the grate-covering at any point.

Another objection to the existing forms of stokers for locomotives is in the specific construction thereof requiring too great height. That is, the top and bottom flights of the grate are separated to such an extent, due to the construction of the individual grates and the consequent size of the sprockets, that the grate interferes with the engine-frame construction in all cases and with the wheels

in certain types of locomotives, or is otherwise placed so high in the boiler that the necessary fire-box volume is reduced. This objection is overcome in the present construction by grates of novel construction, so arranged that sprockets of very small diameter may be employed at the ends of travel of the same. Thus, I am enabled to provide a grate of small thickness transversely.

In order to secure the smallest vertical thickness of the grate a special construction of driving-sprocket is essential. In my construction I provide a sprocket coöperating directly with the grate-members, and also a form or sprocket coöperating with the links which connect the separate grate-bars. By this means the load is carried alternately by the grate-bars and the links connecting the same. By this means also a very small sprocket may be employed. In fact, the upper and lower flights of the grates need to be separated vertically only to an extent substantially equal to the width of one grate-bar. With this construction, I am enabled to provide positive driving-means in the shape of teeth which coöperate with the grate-bars. It is possible to employ a small sprocket if no teeth are used, but it has been found that with a long grate, the square sides do not provide sufficient driving power, frequently slipping past the grate-bars. In any case, a square or flat-sided sprocket, if made of comparatively small diameter has a tendency to bind, due to the spreading or wedging effect in the rotation.

An objection to the installation of stokers to locomotives is the lack of accessibility for the purpose of repairs, either to the grate or to the boiler. It will be understood that the grate lies in a plane along the lower edge or mud-ring of the boiler. This portion of the boiler commonly requires calking to prevent leaks, and, inasmuch as the grate is not adapted to be bodily removed, as in stationary practice, means should be provided whereby portions of the grate may be removed in order to permit access to the mud-ring of the boiler and lower portion of the fire-box. It is further necessary to renew portions of the grate-mechanism from time to time.

In the chain-grate as ordinarily installed, that is, in stationary practice, coal is fed to the grate through a hopper located above the grate, and distribution of the coal through-

out the full length of this hopper, in other words, over the full width of the grate, is obtained by hand-shoveling or by gravity feed, the coal in the latter case being fed 5 from storage hoppers located above the grate. It is my purpose to avoid practically all hand-shoveling, and the construction of locomotives is such that gravity feed is not at all practical, the coal supply on the tender 10 being carried at a height very little above the level of the grate. In the arrangement shown, the coal is conveyed from the tender to the transverse center of the grate at the rear end thereof and is delivered into a space 15 in which transverse spreaders are mounted. These spreaders act to distribute the fuel over the width of the grate and are adjustable vertically, whereby the thickness of fuel can be varied and controlled over the entire 20 width of the grate. This is an important feature, inasmuch as it is quite necessary at times to provide a deeper fire over one portion or another of the grate. This may be accomplished by different means; preferably 25 conveyers or deflectors are provided, which are adjustable vertically from either end, two of such deflectors being mounted at the sides and transverse center of the grate. Each of such deflectors being mounted for 30 vertical adjustment, the height of the fuel may be controlled exactly.

A particular point in connection with the chain-grate proposed is in the means for connecting adjacent grate-bars. The links used 35 are held in place by means other than the usual pins or nuts. In my construction the chain-grate runs between lateral guides, which guides prevent the connecting-links from slipping off the ends of the lugs which 40 are cast integral with the grate-bars, these lugs being the same length as the thickness of the connecting-links with a slight additional allowance for clearance. One of the lateral guides is so constructed that short 45 sections of it may be removed from the supporting-frame work, thereby enabling one or more of the connecting-links of the chain-grate to be removed, which in turn allows the grate-bars to be removed.

50 Claims covering the fuel feeding and spreading mechanism originally disclosed herein are included in my divisional application, Serial No. 857,635.

55 My invention will be more readily understood by reference to the accompanying drawings, wherein.

60 Figure 1 is a plan view of a stoker as applied to a locomotive; Fig. 2 is a longitudinal vertical section through a locomotive fire-box showing the grate in elevation; Fig. 3 is an elevation showing the center support and frame work for the grate; Fig. 4 is a plan view of the construction shown in Fig. 3; Fig. 5 is an enlarged detail elevation, 65 partly in section, of the construction shown

in Figs. 3 and 4; illustrating the removable lateral guides for maintaining the connecting-links in operative relation to the grates; Fig. 6 is a section on line 6—6 of Fig. 5; Fig. 7 is a perspective view of the end of 70 one of the guides shown in Fig. 5; Fig. 8 is a section on line 12—12 of Fig. 2; Fig. 9 is a section on line 13—13 of Fig. 2; Fig. 10 is a section on line 14—14 of Fig. 2; Fig. 11 is a section on line 15—15 of Fig. 2; Fig. 12 is 75 an enlarged detail view showing in elevation the engagement of the grate and the driving sprocket, the links connecting the grates being shown in engagement with one portion of the sprocket; Fig. 13 is a similar view 80 showing the engagement of the grates with another portion of the sprocket, the links being removed; Fig. 14 is a similar view showing the engagement of the sprocket-teeth with the grate-bars, whereby the driving action is secured; Fig. 15 is an enlarged fragmentary plan view of one end of the 85 grate-bar; Fig. 16 is an elevation of the three-plane sprocket used in driving and supporting the grate; Fig. 17 is an edge elevation of one end of a grate-bar; Fig. 18 is an enlarged detail elevation of the distributing deflectors or conveyers showing the means for adjusting the same vertically at the center; and, Fig. 19 is a view similar 90 to Fig. 18 taken at right angles to Fig. 18.

95 Referring more particularly to the drawings it will be seen that my grate is applied to the engine-frame 25 by means of brackets 26, 27, 28, bolted to and projecting above 100 the frame. Mounted upon brackets 26, 27, 28, and securely bolted thereto are side-frames 29, 30, and a center-frame 31 on which the grate is supported. The frames 29, 30, 31 are, as best shown in Fig. 2, made in sections for ease in manufacture and for facility in assembling and removal. The end-portions 32, 33, of the frames carry 105 bearings within which transverse-shafts 34, 35 are mounted, the front-shaft 34 being made preferably in two parts, the rear shaft 35 being made in one part. These shafts carry 110 at their ends my novel driving-sprockets these sprockets being suitably keyed thereto. Each sprocket member is composed of three parts;—a toothed driving part 36, a squared supporting-portion 37 for the grate-bars, and a similar squared portion 38 for the connecting-links. It will be noted that these 115 three parts 36, 37, and 38 are arranged in different planes and each thereof performs a different function. Part 36 has no supporting function, acting merely as a positive drive for the grate. Part 37 acts, as 120 shown in Fig. 13, to directly support the grate-bars, whereas part 38, as shown in Fig. 12 supports the links, the load being alternately carried by the grate-bars and 125 links in the rotation of the sprocket.

130 It will be understood that the grate may

be driven at both ends, that is, by applying power to shafts 34 and 35, however, in the present instance I have deemed this unnecessary and drive only from the shaft 34, the 5 sprockets attached to shaft 35 acting as supporting and alining means. At intervals on the frame members I mount rollers 39 secured to the frame by stub-shafts. This is true except at the high point of the grate 10 shown in Fig. 9. At this point, because of the lack of clearance I have provided integral lugs 40 in place of the rollers.

The grate-bars 41, as shown in Figs. 15 and 17 may be of any preferred construction, but are provided at their ends with integral studs 42 and with the downwardly-projecting integral extension 43, which extension coöperates with the squared portion of the part 37 of the sprocket. Adjacent 20 grate-bars are secured together by means of links 44, these links coöperating with the studs 42. The lower edges of the links and the lower edges of the parts of the extension 43 lying in the same plane provide a 25 continuous flat bearing-surface for contact with the rollers 39 for the upper flight of grates, and, inasmuch as the tops of the links are flush with the tops of the grates a similar continuous bearing-surface is provided for the bottom flights of the grates. 30 At a point inwardly from the ends of the grate-bars, I provide an aperture 41^a with which the toothed part 36 of the sprocket coöperates. It will be noted that this aperture 35 is located inwardly from the ends, and, therefore, that the grate-bar is not weakened as would be the case if the aperture were made through the end-member. It will be further noted that because of this aperture, 40 the air-opening through the grate is not restricted, the aperture 41^a being closed only at the ends of the grate-travel when coöperating with the sprockets. I have shown the sprocket member as four-sided, for the reason 45 that a grate of very small vertical thickness may be utilized. It will be understood, however, that the construction may be changed to provide six or more sides to the sprockets where a deeper grate may be employed. 50 However, the same advantages will accrue to such construction as described in connection with the form shown.

The auxiliary grate heretofore referred to, is shown as composed of four grate-bars 55 45, each grate-bar being of substantially the length of the moving bars, these grate-bars 45 being rotatably mounted on suitable studs projecting inwardly from side-members 46 secured to the side and center members 60 of the fire-box. In the case of the center support, a bearing is provided at the front end on the fire-box and at the rear on a lug forming a portion of the center-frame 65 of the chain-grate, as best shown in Fig. 3. This latter connection is sliding to compen-

sate for expansion and contraction of the boiler. These auxiliary grate-members are provided with shaking-means such as the rods and lever 47, 48. In practice, the fuel is fed on to the grate, burning as it is carried along, and is not completely burned out at the time it reaches the end of travel of the moving grate-bars. It will then pass on to the auxiliary grate where it will be finally consumed. This grate will be 70 shaken from time to time to remove the accumulated ash. By this construction a great objection to the movable grates heretofore proposed for locomotives is removed. 75

As heretofore stated, the movable grate-bars travel between guides, which guides serve to maintain the links 44 in operative relation, thus avoiding the necessity for pins or keys. As shown in Figs. 8, 9, and 10, the center-guide is removable, being held in 80 place by gravity, the outer guides being fixed. In Figs. 4 to 7 inclusive, the construction of the center-guide is illustrated. As heretofore explained, the center-frame 31 is made in sections for convenience, this frame 85 being provided with recesses 49 at intervals in its length within which downwardly-projecting lugs 50 on the guide-members 51 are accommodated. These guide-bars are made in sections, as best shown in Fig. 3, 90 being held in place by gravity. When it is desired to remove one or more grate-bars, one of the sections 51 is removed, thereby permitting the removal of the connecting-links 44. The grate-bar may then be moved 100 horizontally to permit its disengagement from the corresponding link on the opposite end. In this manner any one or more of the grate-bars may be disconnected as required for the purpose of repair or renewal. 105 This likewise gives access to the lower portion of the boiler. The coal is delivered by means of a suitable conveyer operating within a chute 68, which terminates within a coal receptacle formed by a bottom-wall 69, 110 end-walls 70 and top-wall 71, the top-wall forming the firing deck of the locomotive. Within the space formed by these walls coal is delivered by the conveyer, the coal being actually delivered on top of the moving grate which occupies a portion of the space referred to. Within this space my novel distributing means is mounted, this means consisting of a pair of screw-conveyers 72, 73, 115 the inner ends of both conveyers being mounted on a pin or bolt 74 carried by a casting 75, which casting is actuated in ways 76 formed in a bracket 77 suitably secured to the furnace-wall. An adjusting-screw 78 is held by the casting 77, this screw engaging with a threaded-lug 79 on the part 75, the square-end 80 of the screw projecting above the firing-deck. The outer ends of the transverse spreader-screws are likewise provided with vertical adjustable means such as 120 125 130

just described. It will be seen that the deflectors or distributors may be adjusted as to height in order that the depth of coal fed may be controlled as desired. For instance, 5 it sometimes occurs that a higher fire is desired on one side of the boiler than the other and this is provided for in the construction described. It will be noted also that the bearings 81 for the ends of the transverse 10 distributors are connected by means of a plate 82, which serves both as a strengthening means and as a means for leveling the fuel as it passes thereunder.

The transverse-deflectors are actuated by 15 means of suitable chains and sprockets 85 connected to the transverse-shaft 65. The chain-grate is actuated by means of a suitable worm gear 83 connected to a main power-shaft 84, which power-shaft is connected to a small engine, (not shown).

It is obvious that the construction described is capable of modification in many of its details, and such modifications as are within the scope of my claims, I consider 25 within the spirit of my invention.

I claim:

1. In a device of the class described, the combination with a supporting-frame of a plurality of grate-bars, connecting-links for 30 said grate-bars, and removable guide-members supported by said frame, between which said grate-bars are adapted to be moved, and by means of which said connecting-links are maintained in operative relation to said 35 grate-bars, substantially as described.

2. In a device of the class described, the combination of side and center frame-members, guides carried by said members, grate-bars mounted for movement between said 40 guides, links connecting adjacent grate-bars, said links being held in position by coöperation with said guide-bars, substantially as described.

3. In a chain-grate, the combination of 45 connected grate-bars, and a three-plane sprocket over which said grate passes and by means of which the grate is driven, one portion of said sprocket causing the driving of the grate, another portion supporting the

grate-bars, and another portion supporting 50 the connecting-links between adjacent bars, substantially as described.

4. In a chain-grate, the combination of 55 grate-bars, links connecting said bars, and a sprocket over which said grate passes at its limit of travel, said sprocket consisting of a toothed portion and two flat-sided portions, said flat-sided portions being arranged with their flat sides in different planes, one of said flat-sided portions forming a support for the 60 grate-bars and the other flat-sided portion forming a support for connecting-links between adjacent bars, substantially as described.

5. In a device of the class described, the 65 combination with a supporting frame, a plurality of grate bars, links connecting adjacent bars, rigid guide plates associated with said frame and tending to maintain the outer links in position, and a removable 70 guide member at the center and tending to maintain the inner links in position, substantially as described.

6. In a device of the class described, the 75 combination of a frame, a traveling grate, links connecting adjacent grate bars, said 80 grate being divided into a plurality of sections, rigid guide members at the sides of said grate and tending to maintain the outer links in position, and a removable guide 85 member at the center said single guide member serving to maintain the links of adjacent grate sections in place, substantially as described.

7. In a device of the class described, the 85 combination of a frame, a movable grate mounted thereon, links connecting adjacent grate bars, said grate being divided into a plurality of sections, and a removable guide member separating said sections and serving 90 to maintain said links in position said guide member being made up of a plurality of sections, substantially as described.

AUGUSTINE R. AYERS.
